Attorney

UNITED STATES PATENT OFFICE

OTTO H. SCHUH, OF LARAMIE, WYOMING

BASIN WRENCH

Application filed July 7, 1930. Serial No. 465,996.

This invention relates to improvements in basin wrenches of the type employed by plumbers for turning the nut of faucets that are attached to wash basins and sinks.

5 Wash basins and sinks are usually attached to the walls of the kitchen or bath room and the faucets are attached to the same near the wall and in such a position that the nuts that hold the faucets in place cannot be turned by means of the usual wrenches. It is often necessary to repair the faucets and the water pipes connected with them and unless some special wrench is employed, it becomes necessary to remove the sink or wash-15 basin before the nuts can be loosened so as to permit the faucets to be removed.

It is the object of this invention to produce a wrench of a simple and substantial construction that can be made at a small cost 20 and which will be so constructed that it can rotate the nuts in either direction even when they are located in very narrow compartments and which shall also be so constructed that it can be employed in the usual way for 25 any work that an ordinary wrench can be employed for.

This invention briefly described, consists of a handle having one end provided with an enlarged head whose outer surface is serrated and which has one side provided with an inwardly extending opening for the reception of a rotatable plug. An arcuate jaw 30 has one end pivotally attached to the outer end of the plug and has its inner or concave surface provided with transverse serrations. The plug is rotatable about an axis that is at right angles to the axis of the handle and the jaw is movable about a pivot that extends at right angles to the axis of the plug. Since 40 the plug is rotatable through an angle of at least 180 degrees, the jaw can be made to cooperate with the end of the serrated head or with either side thereof. For the purpose of rotating the wrench when it is used as a basin wrench, a tubular handle has been applied to the solid handle of the wrench in such a manner that it can be moved at right angles and used for turning the wrench in a manner which will clearly appear from 45 the description.

Having thus briefly described the invention the same will now be described in detail, and for this purpose reference will be had to the accompanying drawing in which the preferred embodiment of the invention 55 has been illustrated, and in which:

Fig. 1 is a side elevation of my improved wrench with portions of the tubular handle broken away to better show the construction;

Fig. 2 is a side elevation of a wrench showing it in the position which it occupies when employed as a basin wrench;

Fig. 3 is a section taken on line 3—3, Fig. 1;

Fig. 4 is a section taken on line 4—4, Fig. 2; and

Fig. 5 is a view showing a wash basin and showing my improved wrench in position for turning a nut.

In the drawing reference numeral 1 represents the handle of the wrench. This handle is preferably square or rectangular, and is provided at one end with an enlarged head 2, whose sides and end are serrated as indicated by reference numeral 3. The serrations on the sides extend substantially parallel with the axis of the handle, while those on the end extend perpendicular to the axis of the handle and to the axis on which the 80 plug 4 rotates. The plug is provided at its outer end with a flattened portion 5 that extends between the two spaced ears or lug 6 at one end of the arcuate jaw 7. A pin 8 secures the jaw to the flattened portion 5 of 85 the plug and the latter is held against removal by means of a screw 9. The pin can be rotated about its axis so as to bring the jaw into position on either side of the handle as shown in Figs. 2 and 4, or into a position in 90 which it lies in a plane parallel to the axis of the handle as shown in Fig. 1. The inner surface of the jaw is provided with serrations 10 and its outer or convex surface has a rib 11 that serves to strengthen it. When 95 the wrench is in use it engages the nut in the manner indicated by dotted lines in Figs. 1 and 4. With the parts in the position shown in Fig. 1, the nut is rotated in the ordinary way, but when a nut like the one indicated 100

by reference numeral 12 in Fig. 5 is to be rotated, the jaw 7 is moved into position at right angles to the handle so that the jaw may be applied to the nut with the handle projecting downwardly to a point below the basin. For the purpose of turning the wrench when it is used in the manner shown in Fig. 5, I have provided a handle with a tubular sleeve 13 that has a cross section of the proper size and shape to receive the free end of handle 1, which is provided on two sides with grooves 14 whose outer ends are provided with enlarged portions 15. The tubular sleeve 13 has one end cut on a diagonal 16 as shown in Fig. 1. The two sides of member 13 are provided with lugs 17 that extend inwardly and are so positioned that they engage the two grooves as shown in Figs. 1 and 3. If sleeve 13 is pulled outwardly until the lugs come to the enlarged portion 15, the sleeve can then be rotated into the dotted line position and will be held in this position by the action of the lugs. When the sleeve is in the dotted line position shown in Fig. 1 and in the full line position shown in Figs. 2 and 5, the wrench can be rotated about the axis of the handle, by means of the sleeve 13. One end of sleeve 13 is formed into a screw driver 18 and when it is to be used for this purpose, it is usually first removed and then reapplied to the handle with a screwdriver portion outermost.

I want to call particular attention to the sleeve 13 which is interconnected with the wrench handle in such a way that it can be moved from the full line position to the dotted line position shown in Fig. 1 without removing it from the handle. This sleeve cooperates with the arcuate jaw whenever the wrench is employed as a basin wrench and for this reason the movable sleeve constitutes an element of the combination and cooperates with the other parts to perform the function for which the entire assembly is designed.

In Fig. 5 the wrench has been shown in operation and by moving the jaw from the position shown in Fig. 2 to a position in which it lies on the other side of the handle, the wrench can be employed for rotating a nut in the opposite direction and it is therefore suitable for use both in tightening and removing nuts and with the parts in the position shown in Fig. 1, it can be used for any purpose for which a similar wrench can be employed.

Having described the invention what is claimed as new is:

1. A wrench having a handle provided at one end with an enlarged head whose outer surface is provided with projections, the head having an opening extending thereinto from one side thereof, a plug having a cylindrical portion extending into the opening and rotatable therein, and an arcuate jaw

member having one end pivotally attached to the outer end of the plug so that it will swing about an axis perpendicular to the longitudinal axis of the plug, the concave surface of the jaw member having spaced transverse teeth. 70

2. A wrench, for the purpose described, comprising, in combination, a handle having an enlarged head at one end, the outer surface of the head being convex, the sides having a plurality of grooves extending in the general direction of the axis of the handle, and the end having transversely extending grooves, the head having one side provided with a cylindrical opening for the reception of the cylindrical end of a plug, an arcuate jaw member having one end pivoted to the outer end of the plug so as to be movable about an axis that is perpendicular to the axis of rotation of the plug, the inner surface of the jaw member having transverse grooves. 75

In testimony whereof I affix my signature.
